UNITED STATES PATENT OFFICE.

ROBERT S. POTTER, OF GREENWICH, CONNECTICUT, ASSIGNOR TO THE YALE & TOWNE
MANUFACTURING COMPANY, OF STAMFORD, CONNECTICUT.

DOOR CLOSER

Application filed April 22, 1925. Serial No. 25,087

This invention relates to improvements in door closers and more particularly to means cooperable therewith to hold the door in open position,—one object of the invention being to provide simple and efficient means whereby a holding member may be adjustably located with relation to a member carried by the lever arm, and secured in adjusted position to hold the door open to any desired extent.

10 A further object is to avoid the application of a stop or holding member to a band adjustable relatively to the closer casing or its cover, but to utilize the cover itself as the carrying member for the stop or holding member, and

15 to provide readily accessible means for anchoring the casing cover to the casing and yet permit the said cover to be adjusted on the casing to adjust the position of the stop or holding member.

20 With these and other objects in view, the invention consists in certain novel features of construction and combinations of parts as hereinafter set forth and pointed out in the claims.

25 In the accompanying drawings,—

Figure 1 is a plan view of a door stop showing the application of my improvements thereto.

Figure 2 is a sectional view.

30 Figure 3 is a view partly in elevation and partly in section taken at right angles to Figure 2.

Figure 4 is a view in elevation illustrating the clamping band and the manner in which the same is anchored to the closer casing, and

Figure 5 is a detail perspective view of a band section.

In the drawings, 1 represents the casing of a door closer and 2 the cover thereof,—said cover having a peripheral flange 3 to surround the recessed upper end of the casing and said flange is provided with a circumferential groove 4 for a purpose which will be hereinafter explained. The cover 2 has a central opening for the accommodation of the spindle 5 of the closer and for the accommodation of devices between said spindle and the lever arm 6. The lever arm 6 is intended for connection with a door in any approved manner and the devices between this lever arm and the spindle form no part of my present invention and may be of any well known or approved construction.

55 A block 7 is permanently located upon the cover 2 and is provided with a tenon 8 to en-

ter a socket in the cover,—said block or holding member being provided centrally with a curved notch or recess 9 and at respective sides of this notch or recess, the upper face of the block is made convex or inclined as shown at 10. The lever arm 6 is made with a vertical opening 11 through which a plunger 12 is vertically movable. This plunger is recessed in its lower portion for the accommodation of a roller 13, the journals of which are mounted in the plunger at respective sides of said recess. Plunger 12 is so located that the roller may run upon the cover 2 and engage the holding member 7. A spring 14 carried by the lever arm 6 engages under lugs 14^a and enters a notch 15 in the plunger 12 and operates to press the latter downwardly. The tension of this spring may be adjusted by a set screw 16 or in any other suitable manner.

A clamping band 17 surrounds the flange 3 of the cover and is seated in the groove 4 in said flange. This clamping band comprises, in addition to the main portion thereof, a section 18. Respective ends of the main portion of the clamping band are provided with lugs or ears 19 and the respective ends of the band section 18 are provided with lugs or ears 20 which are disposed parallel with the lugs or ears 19. The lugs or ears 19 are provided with holes for the passage of clamping screws 21, the threaded portions of which are screwed through the holes in the lugs or ears 20 of the band section 18. The band section 18 is provided with depending, spaced lugs 22 which receive between them a lug or projection 23 on the case 1. 75 80 85 90

It is apparent that when the door is opened, the roller 13 of the plunger 12 will engage in the notched holding block or member 7 and thus hold the door in open position. In order that the door may be held open to any desired extent, adjustment of the holding member must be provided for. In the present instance, such adjustment may be effected by turning the cap or cover 2. Normally the cap or cover is prevented from being turned by the clamping band and its anchorage to the casing. When it is desired to adjust the cover and hence the holding block, one or both of the screws 21 will be loosened to release the cover from the clamping action of the band. The cover may now be readily turned to adjust the position of the notched holding member. When such adjustment shall have been effected, the band may be

again tightened or clamped to the flange of the cover by tightening the screw or screws 21 and as said band, thus clamped to the flange of the cover, is anchored to the casing so that 5 it can have no rotative movement, the cover will be firmly held in the position to which it may have been adjusted. The clamping screws for the band are always located in the same positions and are readily accessible.

10 Having fully described my invention what I claim as new and desire to secure by Letters Patent, is:

1. The combination with the casing, cover and lever arm of a door closer, of a holding

15 member carried directly by the cover, an engaging member carried by the lever arm for cooperation with said holding member, a clamping band operable to clamp the cover to the casing, and means for anchoring said 20 clamping band to the casing.

2. The combination with the casing, cover and lever arm of a door closer, of a holding member carried directly by the cover, an engaging member carried by the lever arm for cooperation with said holding member, a clamping band operable to clamp said cover to the casing said clamping band comprising 25 a main portion and an inserted section, means for adjustably connecting said main portion

30 and inserted section of said clamping band,

and means for anchoring said inserted section of the clamping band to the casing.

3. The combination with the casing, cover and lever arm of a door closer, of a holding member carried directly by the cover, an engaging member carried by the lever arm for cooperation with said holding member, a sectional clamping band for said cover, means for adjustably connecting said sections, spaced lugs on one of said sections, and a lug 35 on the casing to enter between the spaced lugs on the band section to anchor the clamping band to the casing.

4. The combination with a casing, cover and lever arm of a door closer, said lever arm 45 having lugs on its top between its ends, of a holding member carried by an adjustable part on the casing, a vertically movable plunger carried by the lever arm and cooperative with said holding member, a spring disposed on the lever arm and passing under the lugs thereon, one end portion of said spring engaging said plunger, and an adjusting screw passing upwardly through the lever arm and engaging the opposite end portion 50 of said spring.

In testimony whereof, I have signed this specification.

ROBERT S. POTTER.
